UNITED STATES PATENT OFFICE.

HARRISON J. MITCHELL, OF BELOIT, WISCONSIN, ASSIGNOR TO P. B. YATES MACHINE COMPANY, OF BELOIT, WISCONSIN, A CORPORATION OF WISCONSIN.

TAKE-UP DEVICE FOR SANDER-DRUMS.

1,188,808.

Specification of Letters Patent. Patented June 27, 1916.

Application filed October 6, 1915. Serial No. 54,316.

To all whom it may concern:

Be it known that I, HARRISON J. MITCHELL, a citizen of the United States, residing at Beloit, in the county of Rock 5 and State of Wisconsin, have invented certain new and useful Improvements in Take-Up Devices for Sander-Drums, of which the following is a specification.

It is common in the abrading cylinder or 10 sander drum appliances for smoothly finishing wood, and possibly other materials, to provide a cylinder on which the sheet of sandpaper or other abrading material is spirally or helically wound, and to associate 15 with such cylinder end clamping rings or disks to which the terminal portions of the abrading sheet are secured. It has also been customary to provide such devices with means for manually adjusting or shifting 20 such end members or disks, either simultaneously or independently, for taking up the slack in the abrading sheet to cause the latter to snugly and smoothly fit the surface of the cylinder. Types or samples of 25 such appliances have been fully set forth in United States Patents Nos. 577,582, Lane and Mitchell, abrading cylinder, granted February 27, 1897, and 1,030,897, Lane, abrading cylinder, issued July 2, 1912.

30 One of the leading objects of this invention is to provide an abrading, polishing, or grinding cylinder or drum of this general form with means which will automatically take up the fullness present in, or which is 35 likely to develop in the spiral abrading sheet during service.

A further feature of the invention resides in the construction of parts in such a manner that the end clamping disk may be 40 come displaced slightly out of its normal plane to accommodate itself more readily to the unequal looseness or slack present in the sandpaper.

In order that those skilled in this art may 45 have a full and complete understanding of this invention, the structural characteristics and functional advantages of an appliance embodying the invention, and the manner in which the above-specified and other objects 50 may be attained, I have illustrated a preferred embodiment of this invention in the accompanying drawing, throughout the various views of which like reference characters refer to the same parts, and to which

drawing reference should be had in connection with the following detailed description of the apparatus.

In this drawing: Figure 1 is a fragmentary sectional view of such an abrading cylinder or drum with its cushion and the covering-sheet of sandpaper omitted, and with the means for clamping the ends of such sheet to the end disks omitted; Fig. 2 is a cross-section on line 2--2 of Fig. 1 with the parts viewed in the direction indicated by the arrows; Fig. 3 is an enlarged fragment of Fig. 1; Fig. 4 illustrates one of the pin and diagonally-disposed slot arrangements which translates the longitudinal movement of each of the end disks into a spiral movement; Fig. 5 shows in perspective one of the operating pinions, and Fig. 6 also indicates in perspective a fragment of the operating-shaft and its clutch or ratchet member.

The metal cylinder or drum is composed of a suitable number of alined sections or parts 10, 11, and 12, the two end ones in the device illustrated in the drawing being characterized 10 and 12 respectively. Each of 80 these sections has a cylindrical shell 13 which is centrally connected by a web 14 to an apertured hub 15, all of these sections being driven or fixed on a main-shaft 16, which supports them in proper register and 85 alinement. At each end, this compound or built-up cylinder or drum is equipped with a flanged disk or terminal-element 17 and 18 respectively, each of which is centrally apertured to accommodate the shaft 16 and 90 to permit the rotary and longitudinal adjusting movement of such disk on the shaft. The ends of the strip of sandpaper spirally wound on the drum or cylinder are fastened to these disks by the means illustrated in 95 the patents referred to, or in any other suitable manner, which fastening elements, however, for the sake of clearness of illustration, have been omitted from the present drawing.

The cylindrical hub of the end cylinder section 12 has the hub 19 of a gear 20 rotatably mounted thereon, longitudinal displacement of the gear being prevented by the shoulder 21 of the web and the head of a 105 screw 22. The portion of the hub 19 extending outwardly beyond the end of hub 15 is internally screw-threaded to receive the

right-hand threaded portion of the hub 22 of end-disk 18.

The webs of the various cylinder sections are apertured in alinement for the reception of an operating shaft 23 parallel to the main shaft 16 and equipped at one end with a pinion 24, the teeth of which are in mesh with those of the gear 20. The opposite end of this shaft is squared at 25 for the application of a turning wrench or handle. It is also threaded at 26 for a portion of its length and beyond the threaded part it has fastened thereto by a pin 27 a collar or clutch member 28 having a tooth or ratchet portion 29. An internally-threaded pinion 30 is screwed on to the part 26 of the shaft, its tooth or projection 31 being adapted to bear against and coöperate with the tooth 29. The opposite end of this pinion 30 has a sleeve or shell portion 32 with a pair of slots 33 adapted to co-act with an appropriately-shaped wrench or handle.

As is illustrated in Figs. 1 and 3, the end disk 17 has an aperture at 34 opposite the shaft 23 to permit the introduction of either of the wrenches or handles referred to. Pinion 30 meshes with the teeth of a gear 35, the hub 36 of which is revolubly mounted on the hub of the cylinder section 10 and bears against a shoulder 37 of the web of such section against which it is held by the head of a screw 37a. The part of the hub of gear 35 extending outwardly beyond the hub of section 10 is provided internally with a left-hand screw-thread which coöperates with and receives the correspondingly-threaded hub 38 of an intermediate disk 39, the latter being equipped with four round perforations 40, each of which has fixed therein a shell or cup 41 projecting inwardly toward the gear and having an open mouth facing the end disk 17. Such disk has four pins or rods 42, 42, fixed thereto, each in register with and accommodated in the center of one of the shells 41 projecting through the aperture 43 in the end-wall of the shell and having a tapered head 44, the shank of such pin or rod being somewhat less in diameter than that of the hole 43. Each of these shells houses a coil expansion spring 45 which at one end bears against the inner face of the disk 17, its other end bearing against the bottom or end-wall of shell 41.

As is clearly shown in Fig. 3, the hub 46 of disk 17 is recessed at 47 so as to have a comparatively narrow ring portion 48 bearing on the shaft 16, thus permitting this end disk to rock slightly on the shaft out of its true or normal plane at right-angles thereto. Each of the end disks 17 and 18 has an internally-projecting lug 49 supplied with a diagonally-disposed slot 50 accommodating a pin 51 extending inwardly from the shell portion of the corresponding end section of the cylinder. The slots 50 at the two ends

of the cylinder are oppositely-disposed or inclined so as to occasion opposite spiral movements of the two disks.

Operation: The operation of this appliance occurs substantially as follows: Assuming that the compound or sectional cylinder or drum has been provided with its cushion covering of felt or the like, and that the strip of abradant material or sandpaper has been spirally wound thereon and fastened to the end members 17 and 18, the operator by means of a handle applied to the angular portion 25 of the shaft 23, turns such shaft, rotating the pinion 24 and the pinion 30 by reason of the clutch connection 29, 31. Such rotation of these pinions revolves the gears 20 and 35. This movement of the gear 20 causes an outward feeding of the disk 18 by reason of the right-hand screw connection between the parts 19 and 22 and the disk is at the same time caused to turn angularly on the shaft 16 because of its spiral connection 50, 51 with the drum. Such spiral or helical movement of the part 18 causes the latter to take up the slack or remove fullness from the abradant paper. The turning of gear 35 causes the outward travel of the intermediate disk 39 because of the left-hand screw connection between the parts 36 and 38, and when this member 39 is advanced sufficiently to engage the disk 17, the studs 42 projecting inwardly through the bottoms of the shells 41, it carries the disk 17 along with it, and, by reason of the spiral slot and pin connection 50, 51, of the disk with the cylinder-section 10, the two parts 17 and 39 are caused to turn angularly as they travel axially, that is to say, they will both have a spiral movement the opposite of that given to the disk 18. This action of the disk 17 tightens the sandpaper strip, also removing fullness or slack. Before the member 39 in its axial outward travel engages the disk 17, the latter may have traveled somewhat spirally under the expanding action of the springs 45.

Under ordinary circumstances, soon after the covered cylinder is put to work a looseness will develop in the rear end portion of the abradant sheet, which is secured to the disk 17, and, in order to remove such slack without disturbing the other disk 18 to which the advance end of the paper is secured, the operator applies a suitably-shaped wrench or handle to the parts 32, 33 of the pinion 30 and turns the latter on the shaft 23 without revolving the shaft itself, such partial rotation of the pinion carrying the tooth or shoulder 31 forwardly away from the shoulder 29. This turning of the pinion 125 and the intermeshing gear 35 advances the parts 39 and 17 spirally somewhat farther to eliminate the slack referred to.

During the action of the cylinder in service, a still further slack or looseness in the 130

paper may develop at the end 10 of the cylinder, and this will be automatically taken up by the outward pressing action of the springs 45 which force the disk 17 axially along the 5. shaft and as it moves in this direction, it is compelled to turn angularly by the coöperating parts 50 and 51, the resultant of the two motions being a spiral or helical travel, as indicated above, which is required to 10 properly absorb or take up the fullness referred to. During this automatic take-up of the slack the disk 17 may shift somewhat angularly with respect to the part 39 by reason of the looseness of the fit of the studs 15 42 in the apertures 43, or the part 39 may travel with the part 17, being carried around due to the propelling action of the studs 42.

When the elements referred to are brought back to their initial positions for 20 the replacing of a worn sandpaper sheet with a new one, the conical heads 44 of the pins 42 will act to center or register the members 39 and 17 relatively to one another, all as will be readily understood.

25 It is, of course, difficult, if not impossible, to wrap the sheet of abradant material spirally around the cylinder and have the looseness or slack exactly uniformly distributed around the periphery of the cylinder 30 at its end. It is, therefore, desirable to so construct the take-up device that it can adjust itself to such irregularities and in the present appliances this is accomplished by making the bearing of the disk 17 on the shaft 35 16 so narrow that the disk can turn slightly obliquely to the shaft, which will automatically occur under the action of the springs 45. That is to say, where the slack is greatest, the disk will be freer to rock and such 40 shifting out of its normal right-angle position will be brought about by the expanding action of the springs at those points. As will be readily understood the looseness of fit of the rods 42 in the apertures 43 permits 45 this action to occur without binding of the associated parts.

Although I have herein illustrated and described a preferred embodiment of the invention somewhat in detail, it is to be remembered that the invention is susceptible 50 of a variety of embodiments and that many minor mechanical changes may be made in the structure illustrated without departure from the substance of the invention.

55 I claim:

1. In an abrading-appliance, the combination of a cylinder whose surface is adapted to be spirally covered with a sheet of abradant material, a clamping member at 60 an end of the cylinder, means to fasten the abradant material to said member, and means to automatically shift said member spirally relatively to the cylinder to take up slack in said abradant material, substantially as described.

2. In an abrading-appliance, the combination of a cylinder whose surface is adapted to be spirally covered with a sheet of abradant material, a clamping member at an end of the cylinder, means to fasten the 70 abradant material to said member, and spring-actuated means to automatically shift said member spirally relatively to the cylinder to take up slack in said abradant material, substantially as described. 75

3. In an abrading-appliance, the combination of a cylinder whose surface is adapted to be spirally covered with a sheet of abradant material, a clamping member at an end of the cylinder, means to fasten the 80 abradant material to said member, manually-operated means to shift said member spirally to take up slack in said abradant material, and means to automatically shift said member spirally to take up slack in 85 said material, substantially as described.

4. In an abrading-appliance, the combination of a cylinder whose surface is adapted to be spirally covered with a sheet of abradant material, a clamping member at an 90 end of the cylinder, means to fasten the abradant material to said member, screw-threaded means to shift said member longitudinally of the cylinder, spring-means tending to automatically move said member 95 longitudinally of the cylinder, and means to translate such longitudinal movement of the member into a spiral movement, substantially as described.

5. In an abrading-appliance, the combination of a cylinder whose surface is adapted to be spirally covered with a sheet of abradant material, a clamping member at an end of the cylinder, means to fasten the abradant material to said member, screw-threaded means to shift said member longitudinally of the cylinder, spring-means interposed between said screw-threaded means and said member tending to automatically move said member longitudinally of the cylinder, and means to translate such longitudinal movement into a spiral movement, substantially as described. 100 105 110

6. In an abrading-appliance, the combination of a cylinder whose surface is adapted to be spirally covered with a sheet of abradant material, a clamping member at an end of the cylinder, means to fasten the abradant material to said member, an intermediate member provided with a plurality of 115 apertured sockets, pins fastened to said clamping member and extending through said sockets, springs in said sockets bearing against said clamping member, screw-threaded means to move said clamping and intermediate members longitudinally of the cylinder, and means to translate such longitudinal movement of the clamping-member into a spiral movement thereof, substantially as described. 120 125 130

- 4
7. In an abrading-appliance, the combination of a cylinder whose surface is adapted to be spirally covered with a sheet of abrading-material, a shaft on which said cylinder is mounted, a clamping-member at an end of said cylinder constructed to permit it to shift into a plane slightly oblique to the axis of the shaft, means to secure the abrading material to said clamping member, and means pressing outwardly on said member tending to shift it into an oblique position to compensate for the inequality in the slack in the abrading material, substantially as described.
8. In an abrading-appliance, the combination of a cylinder whose surface is adapted to be spirally covered with a sheet of abrading material, a shaft on which said cylinder is mounted, a clamping-member at an end of said cylinder having a sufficiently narrow bearing on said shaft to permit it to shift into a plane slightly oblique to the axis of the shaft, means to secure the abrading-

material to said clamping-member, and spring means pressing outwardly on said 25 clamping-member tending to shift it into an oblique position to compensate for the inequality in the slack in the abrading material, substantially as described.

9. In an abrading-appliance, the combination of a cylinder whose surface is adapted to be spirally covered with a sheet of abrading material, a clamping member at an end of the cylinder, means to fasten the abrading material to said member, an intermediate member, a loose connection between said clamping and intermediate members, means tending to center said clamping and intermediate members relatively to one another, screw-threaded means to move said 40 clamping and intermediate members longitudinally of the cylinder, and means to translate such longitudinal movement of the clamping member into a spiral movement, substantially as described.

HARRISON J. MITCHELL.
